SEPARABLE CONNECTOR

Filed July 21, 1945

UNITED STATES PATENT OFFICE

2,449,251

SEPARABLE CONNECTOR

Julian Rogoff, New Rochelle, N. Y., assignor to
 Burndy Engineering Company, Inc., a corpora-
 tion of New York

Application July 21, 1945, Serial No. 606,324

8 Claims. (Cl. 287—76)

1

My invention relates to electrical connectors of the quick detachable type which are positively locked together when assembled.

In many forms of electrical wiring it is desirable to provide quick detachable or separable connectors for convenience in servicing, testing or the replacement of portions of such wiring. This is particularly necessary, as an example, in military aircraft, where damaged wire or cable must be replaced quickly, so that the airplane may become serviceable as soon as possible. In such aircraft, it is also desirable that the separable connections do not pull apart or separate accidentally as a result of personnel pulling on the wires while using them as handholds or supports when walking or in the performance of their duties.

Since weight must be saved in military aircraft to the greatest extent possible, and since many separable connectors are used in each airplane, it is very desirable that the separable connectors require no extra wire or cable or "slack" in order to permit them to be opened or closed. My separable connector permits the wires to be actually pulled taut in making the connection.

One object of my invention is to provide such a connector which can be assembled without requiring any slack in the wires or cable which it joins.

Another object of my invention is to provide a separable connector which cannot be pulled apart or otherwise accidentally separated.

Still another object of my invention is to provide a separable connector which can be readily taken apart manually or with the assistance of commonly available tools such as a screwdriver.

A further object of my invention is to provide a separable connector which is easy to manufacture by mass production methods and is low in cost.

I accomplish these and other objects and obtain my new results as will be apparent from the device described in the following specification, particularly pointed out in the claims, and illustrated in the accompanying drawing in which:

Fig. 1 is a perspective view of a separable connector half with open gripper means.

Fig. 2 is a perspective view of my connector with one gripping means in open position.

Fig. 3 is a side elevation of the same with both gripping means in closed position.

Fig. 4 is a bottom view of the same.

Fig. 5 is a sectional view through 5—5 of Fig. 3.

Fig. 6 is a view of a flat terminal portion.

2

Fig. 7 is a perspective view of another pair of flat terminal portions.

My separable connector may consist of two identical halves 10 and 10a which are assembled to each other in actual use, as is shown in Fig. 2. In the drawings elements of connector half 10a will be similarly designated as half 10.

Each half, as shown in Fig. 1 consists of a barrel, or socket portion 11 into which a wire 10 or cable 12 is inserted and attached by either the indentation 13 or by other well known methods. The extending flat tongue 14 may be made by flattening a tube the end of which forms the socket 11, and trimming the edges. A recess 15 is provided adjacent the socket. At the other end of the tongue a U-spring clasp 16, having legs 17 and 18 spaced apart sufficiently to spring clasp the two tongue sections 14 and 14a, is pivotally mounted by means of rivet 19 as shown in Fig. 2. The rivet 19 has a dish-shaped head 20, on the same side of the tongue 14, as contains the recess 15. It has a diameter sufficient to allow it to be positioned in the recess 15a of the interlocking half 10a.

25 The leg 18 of the clasp has an arm 21 which extends eccentrically of the clasp, so that when the clasp is in the closed position, the U-shaped portion will extend transversely across the tongue sections, supported by the pivotally mounted arm. At the end of the arm, a stop tab 22 is formed to prevent the clasp from opening more than 90° from the closed position, at which open position it will engage the edge of the tongue. This facilitates assembly and prevents the clasp 30 from being improperly closed.

Because of the spring clasping pressure sometimes required, screwdriver slots 23 and 24 may be provided in the legs 17 and 18 of the clasp, to assist in the opening and closing of the clasps. 35 Thus when it is difficult to open and close the clasps by hand the blade of a screwdriver may be inserted in one of the slots, and a turning couple exerted in the proper direction, which will cause the clasp to rotate easily.

40 To assemble the two halves of the connection together, it is first necessary to place the springs in the open position as shown in Fig. 1. The tongues 10 and 10a of the two halves are then placed, one over the other, with the dish shaped head 20a resting in the recess 15, and dish shaped head 20 resting in recess 15a. The two clasps 16 and 16a are closed by rotating them 90°, as is illustrated by clasp 16 in Fig. 2.

45 The U-shaped clasps then grip the two tongues together with strong spring pressure, providing

a good "wiping" type of electric contact. At the same time, the rivet heads, locked in the shallow recesses, prevent separation of the two halves as a result of longitudinal or transverse stresses.

In Fig. 6, I have illustrated a modification of one half of my connector to illustrate its use as a terminal. In this view a strip of metal 30 having a width corresponding to the width of a tongue section 14, is provided with an aperture 31, at one end thereof, for attachment to a terminal post, not shown.

At the opposite end a strip is recessed to provide a dish shaped head 32, having a diameter, and being raised from the surface of the tongue, sufficient to allow it to be positioned in the recess 15 of tongue 14, shown in Fig. 1. Between the head 32 and aperture 31, a recess 33 is provided similar to recess 15, and the same distance from projection 32 as recess 15 is from dish shaped head 20. It is thus possible for a connector half such as 10 to be interlocked to the terminal half 30, with clasp 16 when closed operating to keep the two halves interlocked. In such a case only one clasp need be employed to hold the two halves secured together.

A connector half, with its own clasp may be manufactured to terminate in a flat section similar to the end of half 30, with an aperture therein, to provide a terminal lug section where two clasps are required or needed.

In Fig. 7, I have illustrated a section of two flat connector tongue sections 10c and 10e, with a rectangular projection 20c extending from the connector half 10c, and interlocked in aperture 15e, provided in half 10e. Thus a single projection and recess may be employed in place of 2 pairs of each, as shown in Fig. 4, to provide an interlocking means that will prevent any motion in the plane of the abutting tongue sections.

In the foregoing description of my invention I have provided a form of connector having two halves each provided with an engaging face, so that the two halves may be secured to each other laterally, without longitudinal movement, and means for locking the two halves together. The locking means is further distinguished by a wiping action of spring on metal to insure a good electrical connection.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are at-

tained and new results accomplished, as it is obvious that the particular embodiments herein shown and described are only some of the many that can be employed to attain these objects and accomplish these results.

I claim:

1. A connector comprising two portions, each of said portions having a face section for positioning one against the other, interlocking means to prevent movement of the sections in the plane of the respective faces, gripping means for preventing separation of the two portions in a direction normal to the plane of their faces, said gripping means being pivotally mounted on one of said portions and movable in the plane of the faces.
2. The connector of claim 1, wherein the gripping means comprises a clasp for gripping the two portions together.
3. The connector of claim 1, wherein the gripping means comprises a pivotally mounted clasp on each of said portions.
4. The connector of claim 1, wherein the gripping means comprises a pivotally mounted clasp having a recess for inserting a tool therein for applying a turning couple to said clasp.
5. The connector of claim 1, wherein the gripping means comprises a U-shaped spring clasp.
6. A connector comprising two portions, each of said portions having a face section for positioning one against the other; interlocking means to prevent movement of the sections in the plane of the respective faces; and gripping means for preventing separation of the two sections in a direction normal to the plane of their faces; said gripping means being a U-shaped spring clasp applied to said portions in the plane of the faces.
7. The connector of claim 1, wherein the gripping means is U-shaped, one of the legs of the U-shaped gripping means having an extending arm for pivotal connection to the portion.
8. The connector of claim 1, wherein the pivotally mounted gripping means is provided with a stop for limiting the open position of the gripping means.

a good "wiping" type of electric contact. At the same time, the rivet heads, locked in the shallow recesses, prevent separation of the two halves as a result of longitudinal or transverse stresses.

In Fig. 6, I have illustrated a modification of one half of my connector to illustrate its use as a terminal. In this view a strip of metal 30 having a width corresponding to the width of a tongue section 14, is provided with an aperture 31, at one end thereof, for attachment to a terminal post, not shown.

At the opposite end a strip is recessed to provide a dish shaped head 32, having a diameter, and being raised from the surface of the tongue, sufficient to allow it to be positioned in the recess 15 of tongue 14, shown in Fig. 1. Between the head 32 and aperture 31, a recess 33 is provided similar to recess 15, and the same distance from projection 32 as recess 15 is from dish shaped head 20. It is thus possible for a connector half such as 10 to be interlocked to the terminal half 30, with clasp 16 when closed operating to keep the two halves interlocked. In such a case only one clasp need be employed to hold the two halves secured together.

A connector half, with its own clasp may be manufactured to terminate in a flat section similar to the end of half 30, with an aperture therein, to provide a terminal lug section where two clasps are required or needed.

In Fig. 7, I have illustrated a section of two flat connector tongue sections 10c and 10e, with a rectangular projection 20c extending from the connector half 10c, and interlocked in aperture 15e, provided in half 10e. Thus a single projection and recess may be employed in place of 2 pairs of each, as shown in Fig. 4, to provide an interlocking means that will prevent any motion in the plane of the abutting tongue sections.

In the foregoing description of my invention I have provided a form of connector having two halves each provided with an engaging face, so that the two halves may be secured to each other laterally, without longitudinal movement, and means for locking the two halves together. The locking means is further distinguished by a wiping action of spring on metal to insure a good electrical connection.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are at-

tained and new results accomplished, as it is obvious that the particular embodiments herein shown and described are only some of the many that can be employed to attain these objects and accomplish these results.

I claim:

1. A connector comprising two portions, each of said portions having a face section for positioning one against the other, interlocking means to prevent movement of the sections in the plane of the respective faces, gripping means for preventing separation of the two portions in a direction normal to the plane of their faces, said gripping means being pivotally mounted on one of said portions and movable in the plane of the faces.

2. The connector of claim 1, wherein the gripping means comprises a clasp for gripping the two portions together.

3. The connector of claim 1, wherein the gripping means comprises a pivotally mounted clasp on each of said portions.

4. The connector of claim 1, wherein the gripping means comprises a pivotally mounted clasp having a recess for inserting a tool therein for applying a turning couple to said clasp.

5. The connector of claim 1, wherein the gripping means comprises a U-shaped spring clasp.

6. A connector comprising two portions, each of said portions having a face section for positioning one against the other; interlocking means to prevent movement of the sections in the plane of the respective faces; and gripping means for preventing separation of the two sections in a direction normal to the plane of their faces; said gripping means being a U-shaped spring clasp applied to said portions in the plane of the faces.

7. The connector of claim 1, wherein the gripping means is U-shaped, one of the legs of the U-shaped gripping means having an extending arm for pivotal connection to the portion.

8. The connector of claim 1, wherein the pivotally mounted gripping means is provided with a stop for limiting the open position of the gripping means.
